E. B. MERRIAM,
ELECTRIC SWITCH,
APPLICATION FILED JUNE 7, 1916.

1,306,551.

Patented June 10, 1919.

Inventor:
Ezra B. Merriam,
by *Alfred S. Davis*,
His Attorney.

UNITED STATES PATENT OFFICE.

EZRA B. MERRIAM, OF SCHENECTADY, NEW YORK, ASSIGNOR TO GENERAL ELECTRIC COMPANY, A CORPORATION OF NEW YORK.

ELECTRIC SWITCH.

1,306,551.

Specification of Letters Patent. Patented June 10, 1919.

Application filed June 7, 1916. Serial No. 102,211.

To all whom it may concern:

Be it known that I, EZRA B. MERRIAM, a citizen of the United States, residing at Schenectady, in the county of Schenectady, 5 State of New York, have invented certain new and useful Improvements in Electric Switches, of which the following is a specification.

My invention relates to electric switches 10 and in particular to electric switches in which the contacts are opened beneath the surface of oil or other insulating fluid.

The object of my invention is to provide a novel and improved electric switch of the 15 oil break type and more specifically to provide an oil break switch having novel and improved means for preventing the ejection of oil from such switches under the pressures existing in the switches when the contacts separate and for absorbing the energy 20 of the oil within the switch.

In switches in which the contacts separate under oil, various means have been suggested and have been used for baffling the 25 oil within the switch consisting of plates having staggered openings and other arrangements for decreasing the velocity of the oil. I provide however a different type of means than heretofore known which operates as an energy absorbing device to catch the oil and absorb its energy within the 30 switch.

My invention will best be understood in connection with the accompanying drawings 35 in which, merely for purposes of illustration, I have shown some of the various forms in which my invention may be embodied and in which Figure 1 is a vertical section of one form of switch constructed in accordance with my invention; Figs. 2, 3, 4 and 5 are plan views of portions of my switch shown in Fig. 1; Fig. 6 is a sectional view of a portion of a similar form of switch, embodying my invention in a modified form; 45 Fig. 7 is a detail view of a portion of the switch shown in Fig. 6; Fig. 8 is a sectional view of a portion of a switch showing another embodiment of my invention; Figs. 9, 10, and 11 are plan views of parts of the 50 switch shown in Fig. 8; and Fig. 12 is a sectional view of a portion of a similar form

of switch embodying still another form of my invention.

The particular form of switch in which I have shown my invention embodied, as 55 best shown in Fig. 1, comprises an oil pot or vessel made of metal and lined with insulation, and containing oil or other suitable insulating fluid in which the circuit is opened. The circuit is controlled by 60 means of two relatively movable co-operating contacts, such as a stationary or fixed contact or contact member 2 mounted at the bottom of the oil pot 1 and a movable contact or contact member 3 in the form of a 65 rod movable longitudinally of the oil pot 1 by any suitable mechanism and slidably mounted in a hollow insulator 4 carried by the top of the oil pot. The separation of the contacts draws an arc in the insulating 70 fluid, and the pressure produced by the arc is relieved by means of suitable vents 5 in the top of the oil pot. The insulating fluid is retained in the neighborhood of the arc and is directed against the arc to extinguish 75 it, by means of a member or partition 6 provided with an opening or vent 7 and mounted above the fixed contact 2 with its edges in engagement with the lining of the oil pot 1, so that the fixed contact 2 is inclosed 80 in a pressure retaining chamber or vessel of which the partition 6 forms one wall and in which the oil is put under pressure by the action of the arc formed between the contacts as the circuit is being opened. The 85 partition is held in place against pressure generated by the arc in the pressure retaining chamber by suitable supporting members 8.

When a switch constructed as above de- 90 scribed is opened, the movable contact 3 separates from the fixed contact 2 and moves upward through the opening 7 in the plate or member 6, thereby drawing an arc through the opening. The member 6 confines the oil 95 put under pressure by the arc, in the pressure retaining chamber and directs it through the vent 7 against the arc to extinguish it, with the result that the oil and gases are projected through the vent 7 in a 100 jet or stream which tends to spread out like a fountain.

In accordance with my invention, I provide means within the oil vessel whereby the oil and gases ejected from the pressure retaining chamber are separated and the 5 gases allowed to escape from the oil pot while the oil is intercepted and directed to the sides of the vessel where its energy is absorbed in pocket or intercepting members.

This energy absorbing means consists of 10 intercepting members or plates 9 and 10 and a baffle plate 11 which are suitably secured to supporting members 8 within the oil pot and which are provided with central openings 12, 13 and 14, respectively, as best 15 shown in Figs. 2, 3 and 4, respectively. The intercepting members 9 and 10 are mounted substantially in engagement with the sides of the oil pot and are of a configuration forming an annular pocket or recess between 20 the sides of the oil pot and the openings 12 and 13, concentric with the movable contact 3 and with the openings. These bell shaped interceptors are made of metal and at the top of each pocket or recess of the interceptors 25 are perforations 15 to allow the escape of any entrapped gases. As the oil and gases are ejected from the pressure retaining chamber through the vent 7, the oil spreads out like a fountain and is directed upward 30 into the pockets of the bell shaped interceptor 9 while most of the gases and some of the oil follows the movable contact 3 through the opening 12 in interceptor 9. The opening 13 in the intercepting member 35 10 is much smaller than the opening 12, the movable contact 3 passing through this opening with only slight clearance. Owing to the smaller opening 13 in the member 10, the pocket or recess of member 10 is somewhat 40 larger, the inner sides of the pocket extending farther toward the center of the oil pot and into the oil stream. The oil, therefore, that rises through the opening 12 in interceptor 9 is thereby deflected into the pocket 45 of member 10 and the gases, if they have not already spent their velocity, follow the movable contact through opening 13 of interceptor 10 and around baffle 11 and finally 50 through vents 5 out of the oil pot. If, under unusual circumstances, there is some oil ejected through the opening 13 of interceptor 10, this oil strikes the baffle 11 and is deflected and prevented from escaping 55 through the vents 5.

By my novel energy absorbing means described, the oil is not caused to follow a tortuous path or is it splashed about by striking flat baffle plates but the oil is directed into the pockets of the bell shaped interceptors 60 9 and 10 which act to catch the oil and absorb its energy in the same manner as the pocket formed in a base ball glove catches a base ball. The oil is caught by these pockets or recesses, its energy absorbed 65 and then the oil allowed to drop back into

the oil pot and into the oil reservoir. If any gases are entrapped with the oil in the pockets of members 9 and 10 such gases escape through the perforations 15. The interceptors 9 and 10, being of metal, act to 70 cool the heated oil and arc gases and prevent thereby the liability of explosions in the switch. The difference in principle and in operation between the interception of the upwardly ejected oil by the bell shaped interceptors 9 and 10, and the absorption of 75 its energy and the baffling action of substantially flat baffles of ordinary construction may be compared in principle to the pouring of a liquid upon a flat plate or into 80 a basin. With a flat plate, the liquid is deflected in all directions, whereas in a basin the fluid is not deflected but is caught and retained therein. In a switch having the ordinary baffle construction, the oil is ejected 85 upward against a substantially flat surface and is deflected in all directions wherein with the bell shaped interceptors, the oil is not deflected but is caught and its energy expended and then the oil is allowed to 90 freely fall into the oil reservoir at the bottom of the oil pot. My energy absorbing means and the members 6 and 11 with their supporting members 8 are arranged in unit construction, which unit is removably positioned in the oil pot. 95

In Fig. 6, I have shown a slightly different form of my energy absorbing device embodied in a switch of the same type as that shown in Fig. 1. In this device, the interceptor 9 is smaller than the corresponding interceptor shown in Fig. 1 having a smaller central opening 12 and is spaced away from the walls of the oil pot 1 whereby a greater portion of the oil ejected from opening 7 105 is caught in the pocket of the interceptor. This interceptor is more clearly shown in Fig. 7. The metallic bell shaped intercepting members may be made, in general, in two forms differing only slightly from each 110 other in configuration. The members 9 and 10 shown in Figs. 1 and 6 are spun into the desired shape whereas the interceptors 16 and 17 shown in Fig. 8, for switches operating in higher potential circuits, are cast 115 in the desired shape with perforations 15, the cast members being of a little more rugged construction. The interceptors 16 and 17 are shown more in detail in Figs. 10 and 11 respectively and are provided with 120 central openings, into which openings insulating members or sleeves 18 and 19 are respectively inserted, which sleeves are preferably substantially tubular in form to produce cylindrical or tubular openings or passages 20 and 21 respectively through which the movable contact member 3 passes, the insulating members 18 and 19 serving to insulate the movable contact from the metal interceptors. In this construction an extra 125 130

baffle plate 22 is provided at the top of the oil pot adjacent the vents 5 and having a central opening 23 as best shown in Fig. 9.

In Fig. 12, I have shown my energy absorbing means as comprising an intercepting member of slightly different configuration. In this construction mounted on the partition or member 6 and insulated therefrom is a deflecting member 24, preferably of substantially inverted conical shape, having an opening adjacent and in alinement with the opening 7 in member 6. The opening in the deflector 24 is much smaller than the opening 7 so that the flaring sides of the deflector extend into the path of the upward stream of oil and act to deflect the oil to the sides of the oil pot 1. Mounted near the top of the oil pot 1 is an intercepting member 25, the inner sides of which extend down the center of the oil pot to form between the sides a central elongated or tubular chamber. The interceptor 25 has an opening 26 which is adjacent and just above the deflector 24, the edges of the opening being turned in somewhat to deflect the oil. Between the inner sides of the interceptor 25 and the walls of the oil pot 1 is formed an annular passage closed at its upper end and forming a very deep pocket into which the oil is directed by the deflector 24, and its energy absorbed in the same manner as already described. By this construction, the oil is deflected into one interceptor having a deep recess or pocket while the arc gases are separated from the oil and rise through the center of the oil pot following the moving contact into the elongated chamber formed by the sides of the deflector 25.

My invention may be embodied in other forms than those shown and described and I, therefore, do not wish to be restricted to the precise construction disclosed but intend to cover by the appended claims changes and modifications which are within the scope of my invention and will be apparent to those skilled in the art.

What I claim as new and desire to secure by Letters Patent of the United States, is:

1. A circuit interrupting device comprising a pressure retaining chamber for containing oil and having a vent in one wall thereof, relatively movable coöperating contacts separable in said chamber, means for absorbing the energy of the oil ejected from said vent as said contacts separate comprising intercepting members shaped to provide annular pockets into which the oil is deflected and its energy absorbed.

2. A circuit interrupting device comprising a pressure retaining chamber for containing oil and having a vent in one wall thereof, relatively movable coöperating contacts separable in said chamber, intercepting means above said vent comprising bell shaped members for catching the oil ejected

from said vent as said contacts separate and absorbing its energy within the interrupting device.

3. A circuit interrupting device comprising a pressure retaining chamber for containing oil and having a vent in one wall thereof, relatively movable coöperating contacts separable in said chamber, metallic bell shaped members mounted in the space above said vent and provided with substantially closed annular pockets into which the oil is directed as it is ejected from said vent and its energy absorbed. 75

4. A circuit interrupting device comprising a vessel containing oil, a pressure retaining chamber within said vessel having a vent in one wall thereof, relatively movable coöperating contacts separable in said chamber, an energy absorbing means for the oil ejected through said vent as said contacts 80 separate comprising a unitary structure removably positioned within said oil vessel and consisting of bell shaped intercepting members having central openings through which the movable contact passes, said intercepting members being provided with annular recesses into which the oil is deflected and its energy absorbed. 85 90

5. An oil switch comprising a vessel for containing oil, a pressure retaining chamber within said vessel having a vent in one wall thereof, relatively movable coöperating contacts separable in said chamber, means for absorbing the energy of the oil as it is ejected through said vent comprising metallic bell shaped interceptors mounted substantially in engagement with the sides of said oil vessel and having central openings, said interceptors forming pockets concentric with said openings having perforations at the 95 tops thereof, insulating members mounted in said openings and providing cylindrical passages through which said movable contact passes. 100

6. An oil switch comprising a vessel for 110 containing oil, a pressure retaining chamber within said vessel having a vent in one wall thereof, relatively movable coöperating contacts separable in said chamber, a bell shaped member mounted between said vent 115 and the top of the oil vessel substantially closing said vessel except for a central opening in said member, said member being shaped to provide an annular pocket for catching and intercepting the oil as it is 120 ejected upward whereby the energy of the oil is absorbed within the switch.

7. An oil switch comprising a pressure retaining chamber containing oil and having a vent in one wall thereof, fixed and 125 movable coöperating contacts separable in said chamber, a bell shaped intercepting member mounted above said pressure retaining chamber provided with a central opening and forming a pocket concentric there- 130

with, a second bell shaped intercepting member mounted above said first mentioned member provided with a central opening through which said movable contact passes
5 with slight clearance and forming a pocket concentric therewith, the sides of said pocket adjacent said opening extending into the path of fluid ejected through the opening of

said first mentioned intercepting member, said pockets constituting said bell shaped 10 members acting to catch the oil and absorb its energy.

In witness whereof, I have hereunto set my hand this 5th day of June, 1916.

EZRA B. MERRIAM.
